UNITED STATES PATENT OFFICE.

JAMES FREDRICK CALDWELL, OF LOS ANGELES, CALIFORNIA.

MOLDING MACHINE.

Application filed April 5, 1922. Serial No. 549,749.

To all whom it may concern:

Be it known that I, JAMES F. CALDWELL, a citizen of the United States, and resident of Los Angeles, in the county of Los Angeles and State of California, have invented certain new and useful Improvements in Molding Machines, of which the following is a specification.

This invention relates to block molds especially adapted for use in the manufacture of gypsum blocks used for partition walls and other exterior work.

In the manufacture of gypsum blocks the same has a tendency to adhere to the interior walls of the mold and the blocks frequently break upon being removed from the mold and the object of this invention is to provide simple and reliable means whereby the blocks upon being formed may be removed from the mold without the possibility of breaking or adhering to the wall of the mold.

A further object is to provide a mold for gypsum blocks having simple means whereby the end walls of the mold are moved outwardly immediately upon the completion of the removal of the core, the outward movement of the end walls being brought about by the movement of the same lever which removes the core, thereby greatly expediting the removal of the block from the mold.

A further object is to provide a gypsum block or tile mold which is of highly simplified construction, durable in use and cheap to manufacture.

Other objects and advantages of the invention will be apparent during the course of the following description.

In the accompanying drawing forming a part of this application and in which like numerals are employed to designate like parts throughout the same,

Figure 1 is a side elevation of the improved mold.

Figure 2 is a plan view thereof.

Figure 3 is a fragmentary perspective of a pair of wedge-shaped cores embodied in the invention.

Figure 4 is a perspective of a hammer embodied in the invention, the said hammer

being adapted for tapping the ends of the cores whereby to release the same from the walls of the block.

Figure 5 is a fragmentary perspective of a lever and a link employed for swinging the end walls outwardly subsequent to the removal of the cores.

Figure 6 is a detailed view illustrating a modified form of hammer.

In the drawing the numeral 5 designates what might be said to be a platform or base having its longitudinal edges rigidly connected to spaced parallel side bars 7, the said side bars being extended for substantial distances beyond the ends of the bottom wall 6.

The mold consists of a pair of spaced parallel side walls 8 horizontally hinged at their lower edges to the side bars 7 by means of hinges 9. The side walls 8 of the mold are releasably held in an upright position by means of lugs 11 carried by the vertical edge portion of the end walls 12. The end walls 12 are horizontally hinged to the side bars 7 as indicated at 13 and are capable of being swung outwardly to a limited extent so as to permit of the removal of the block.

After the block has been formed a pair of wedge-shaped cores 15 are removed from the mold so as to permit the block to be moved laterally or vertically. Fig. 1 illustrates that the wedge-shaped cores 15 are extended longitudinally through the end walls 12 and are of course securely held in position by the openings in the end walls. That is to say the openings which receive the wedge-shaped cores 15 are of a size to snugly receive the cores so that the cores cannot move laterally.

When it is desired to release the cores 15 a hammer 16 is drawn rearwardly by means of a handle 17 and is then released so that it will swing into engagement with the extended ends of the cores 15. The hammer 16 is supported at the upper end of a lever 20 connected intermediate its ends to a pivot bar 21, the said pivot bar being connected at its ends to the side bars 7. The lower portion of the lever 20, is as illustrated in Figure 1, connected to a coiled spring 24.

anchored to a cross bar 25 also connected to the side bars 7. The coiled spring 24 is of sufficient stoutness to cause the hammer 16 to release the cores 15 from binding engagement with the tile within the mold.

It is thus seen that the cores 15 are positioned as illustrated in Figure 1 and that subsequent to the filling of the mold the cores 15 are released by pulling back the hammer 16 and subsequently releasing the same whereby the hammer slides into engagement with the extended ends of the core.

When the cores 15 have been loosened by means of the hammer 16 the same may be conveniently withdrawn by the operation of a lever 30 pivoted intermediate its ends to a shaft 31 carried by the side bars 7. The lower portion of the lever 30 is pivoted to a link 33 connected at its forward end to an attaching strip or plate 34. The member 34 is securely connected to the ends of the wedge-shaped cores 15 so that when the link 33 is moved longitudinally the cores will be withdrawn.

The cores 15 which are arranged in superposed relation are carried by guides 36 which are in turn connected to standards 37 mounted on the extended portions of the side bars 7.

As the lever 30 approaches the limit of its rearward movement it engages the cross head 40 of a lever 41, the said lever being provided with means to swing the end walls 12 outwardly. As illustrated in Figure 5 the cross head 40 which is engaged by the bend 45 in the lever 30 is provided with a downwardly directed terminal portion 47 to which a link 48 is pivoted. This link 48 is in turn pivoted to one of the end walls 12 so that when the cross head 40 is moved rearwardly the end wall 12 will be moved outwardly.

The lever 41 might be said to be divided into two branches, one of which is curved longitudinally and provided with a cross head 40 while the other one is connected to a link 50 connected to an end wall releasing lever 51 having its lower portion provided with a laterally directed bend 53 secured to the link 50 by a pivotal connection.

When the cross head 40 is released by the lever 30 the spring 56 connected to the terminal portion 47 and the curved branch of the lever promptly returns the lever 41 to its original position whereby the end walls 12 are simultaneously returned to their upright or original positions.

When the end walls 12 have been moved outwardly the side walls may also be moved outwardly by means of releasing bars 60 having attaching straps 62 rigidly connected to the intermediate portions of the side walls. The releasing bars, of which there are two are rotatably secured to the side bars 7 by

means of brackets 65 and have their rear terminal portions formed with upwardly directed handles 68 by means of which the side walls 8 may be swung outwardly.

A machine constructed in accordance with this invention is especially adapted for use in the manufacture of gypsum blocks and in operation the gypsum is placed in the molds and is formed into hollow blocks or tiles thereby. Upon the formation of the block the extended ends of the cores 15 are tapped by the hammer 16 whereupon the same are released from engagement with the interior of the block. The cores 15 may now be conveniently withdrawn by means of the lever 80 30 and as previously stated when the lever reaches the limit of its movement or when it approaches the limit of its movement the cross head 40 is engaged whereby the lever 41 is operated for swinging the end walls 12 outwardly. After the end walls have been swung outwardly the side walls may also be swung outwardly, thereby exposing the blocks and permitting the same to be conveniently withdrawn.

In use the block will not in any way adhere to the walls of the mold because of the particular construction provided.

In carrying out the invention the machine may be mounted on standards 70 having wheels 71 mounted on tracks 72. When filling the mold it may be arranged in one position and when it is desired to discharge the block or remove the same the entire machine may be moved on the tracks 72 to a suitable point of discharge. In fact a battery of machines may be provided on an equal number of tracks and the space beneath the tracks is left clear to allow the levers to operate with freedom.

Also in carrying out the invention an air operated hammer 90 may be provided for tapping the ends of the cores. The air operated hammer is provided with an air hose 91 which may extend from a suitable source of supply.

Having thus described the invention, what I claim is:—

1. A block manufacturing machine comprising a pair of side bars, side and end walls horizontally hinged to said side bars, tapered cores slidable through said end walls and securely held in position thereby, and a spring actuated hammer adapted to engage the extended ends of said cores whereby to release the same from engagement with the blocks.

2. A block manufacturing machine comprising a pair of side bars, side and end walls horizontally hinged to said side bars, tapered cores slidably through said end walls and securely held in position thereby, a spring actuated hammer adapted to engage the extended ends of said cores whereby to release the same from engagement with the

blocks, a lever supported for rocking movement by said side bars, a link connected to said lever, and means connecting said link to the ends of said cores whereby the operation 5 of the lever withdraws said cores.

3. A block manufacturing machine comprising a pair of side bars, side and end walls horizontally hinged to said side bars, tapered cores slidable through said end walls 10 and securely held in position thereby, a spring actuated hammer adapted to engage the extended ends of said cores whereby to release the same from engagement with the blocks, a lever supported for rocking 15 movement by said side bars, a link connected to said lever, means connecting said link to the ends of said cores whereby the operation of the lever withdrawn said cores, a second lever connected to said side bars and 20 having a cross head arranged in the path of travel of said first named lever, and means connecting said second named lever to said end walls whereby the rocking movement of said first named lever will rock said 25 second named lever and move the end walls outwardly.

4. A block manufacturing machine comprising a pair of side bars, side and end walls horizontally hinged to said side bars, 30 tapered cores slidable through said end walls and securely held in position thereby, a spring actuated hammer adapted to engage the extended ends of said cores whereby to release the same from engagement with the blocks, a lever supported for rocking movement by said side bars, a link connected to 35 said lever, means connecting said link to the ends of said cores whereby the operation of the lever withdraws said cores, a second lever connected to said side bars and 40 having a cross head arranged in the path of travel of said first named lever, means connecting said second named lever to said end walls whereby the rocking movement of said first named lever will rock said 45 second named lever and move the end walls outwardly, and spring means connected to said second named lever and said side bars for returning the end walls to their upright 50 positions.

5. A block manufacturing machine comprising a pair of side bars, side and end walls horizontally hinged to said side bars, tapered cores slidable through said end walls 55 and securely held in position thereby, a spring actuated hammer adapted to engage the extended ends of said cores whereby to release the same from engagement with the blocks, a lever supported for rocking 60 movement by said side bars, a link connected to said lever, means connecting said link to the ends of said cores whereby the operation of the lever withdraws said cores, a second lever connected to said side bars and 65 having a cross head arranged in the

path of travel of said first named lever, means connecting said second named lever to said end walls whereby the rocking movement of said first named lever will rock said second named lever and move the end 70 walls outwardly, spring means connected to said second named lever and said side bars for returning the end walls to their upright positions, and guiding means supported by said side bars and slidably receiving 75 said cores.

6. A machine for manufacturing gypsum blocks comprising a platform, side bars secured to the platform and extended for substantial distances beyond the opposite ends 80 of the same, side and end walls horizontally hinged to said side bars, the end walls being provided with openings, tapered cores received in said openings and having their ends extended beyond the walls, a lever supported by said side bars and having a cross head, a link connecting said cross head to one of said end walls, means connecting one end of said lever to the other end wall, coiled springs connected to said lever and 85 said side bars for returning the end walls to their upright positions and a core releasing lever carried by said side bars and adapted to engage said cross head whereby to operate the first named lever. 90

7. A machine for manufacturing gypsum blocks comprising a platform, side bars secured to the platform and extended for substantial distances beyond the opposite ends 95 of the same, side and end walls horizontally hinged to said side bars, the end walls being provided with openings, tapered cores received in said openings and having their ends extended beyond the walls, a lever supported by said side bars and having a cross head, a link connecting one end of said lever to the other end wall, coiled springs connected to said lever and said side bars for returning the end walls to their upright 100 positions and a core releasing lever carried by said side bars and adapted to engage said cross head whereby to operate the first named lever, and side wall releasing bars rotatably carried by said side bars and having upwardly directed terminal portions constituting handles. 105

8. A machine for manufacturing gypsum blocks comprising a platform, side bars secured to the platform and extended for substantial distances beyond the opposite ends 110 of the same, side and end walls horizontally hinged to said side bars, the end walls being provided with openings, tapered cores received in said openings and having their ends extended beyond the walls, a lever supported by said side bars and having a cross head, a link connecting one end of said lever to the other end wall, coiled springs connected to said lever and said side bars for returning the end walls to their upright 115 positions and having a cross head arranged in the

tions, a core releasing lever carried by said side bars and adapted to engage said cross head whereby to operate the first named lever, side wall releasing bars rotatably carried by said side bars and having upwardly directed terminal portions constituting handles, and a spring actuated hammer

adapted to engage the extended ends of said cores and having a lever, and spring means connected to the last named lever for urging the hammer into engagement with the ends of the cores.

JAMES FREDRICK CALDWELL.
